UNITED STATES PATENT OFFICE.

ORVILL W. BROWN, OF HAYT'S CORNERS, ASSIGNOR OF ONE-THIRD TO
GEORGE W. B. NEAL, OF OVID CENTRE, NEW YORK.

RAILROAD-TIE.

SPECIFICATION forming part of Letters Patent No. 425,747, dated April 15, 1890.

Application filed December 12, 1889. Serial No. 333,519. (No model.)

To all whom it may concern:

Be it known that I, ORVILL W. BROWN, a citizen of the United States of America, residing at Hayt's Corners, in the county of Seneca 5 and State of New York, have invented certain new and useful Improvements in Railroad-Ties, of which the following is a specification, reference being had therein to the accompanying drawings.

10 My invention relates to improvements in railroad-ties, and the leading object of my invention is the provision of a tie which will wear for a long period and which may be produced at such a cost as to enable it to be 15 used in place of the ordinary tie now employed.

A further object of my invention is the provision of a cheap and durable tie, which will provide an elastic bed for the tracks, 20 whereby the trains will travel smoothly and to the comfort of the passengers.

25 A further object is the provision of a tie which cannot be injured by the damaging influences of the weather, and thus produce a dry bed for the trains and effectually prevent collapse of the tie and derailment of the trains.

To attain the desired object the invention consists of a tie constructed substantially as 30 herein illustrated, described, and specifically pointed out in the claims.

In the accompanying drawings I have shown a tie constructed in accordance with and embodying my invention, although I 35 may make slight changes in the form and proportion of parts thereof without departing from the scope of my invention, and in said drawings Figure 1 represents a perspective view of my novel and improved railroad-tie. Fig. 2 represents a plan view thereof. Fig. 3 represents a longitudinal section on line $\alpha\alpha$ of Fig. 2. Fig. 4 represents a transverse section on line yy of Fig. 3.

40 My railroad-tie consists of a box, tube, or case formed of metal suitable for the purpose having a flat bottom or base A, a semicircular or arc-shaped upper part A', the corners of the case A² being somewhat rounded, as clearly shown.

45 50 In the rounded top of the case I form

sockets or seats A³ of such a size as to allow the feet of the rails to fit snugly therein, and on each side of the seats I provide openings A⁴ to receive fastening-spikes B, the heads of which thus engage one on each side 55 of the base of a rail and thus secure the rail in place. The spike-openings, it will be seen, are arranged diagonally with relation to each other, as I believe by thus placing the spikes they retain the rail more firmly, and the 60 weight of the train is more evenly distributed.

I place within the tube or case a bar or bars C, of wood, which are substantially rectangular, the upper corners C' being rounded to fit snugly against the surface of the tube 65 or case and the square upper face C² of the bar or block forming a bed for the rails to rest upon. It will thus be seen that the rail rests on a bed somewhat flexible or elastic, and thereby gives slightly, imparting a comfortable and easy riding of the train. It 70 will also be noted that the block or blocks rest on a metallic surface and cannot collapse, that they are shielded from the weather, and that spaces are provided between the 75 case and block which allow a free circulation of air around the block to keep it dry and prevent rotting. It is also evident that while the tie possesses these features of merit, in addition thereto it can be manufactured at 80 a low figure and thus be a valuable and practical article for the intended purpose.

I claim as my invention—

1. A railroad-tie consisting of a tube or case having a flat base and rounded top, a 85 block or blocks fitting therein having their bottom and upper corners engaging, respectively, the bottom and top of the tube.

2. A railroad-tie consisting of a case or box having an upper rounded portion provided with rail seats or sockets, a block or bar fitting in said case and having a flat surface below the seats in the rounded portion of the case to form a flat bed for the rails, and fastenings for securing the rails to the 95 case and block.

3. A railroad-tie consisting of a substantially round case or box having seats or sockets therein for the rails, a substantially rectangular block or blocks fitting in said 100

case or box, and fastenings for securing the rails to the case and block.

4. In a railroad-tie, the combination of the box or case having seats therein, the block fitting in said case to provide spaces between it and the case, the rails having their base fitting in the seats of the case and resting on the block, and the spikes passing through the case into the block, having their heads

engaging the base of the rail, and arranged to at an angle or diagonally to each other.

In testimony whereof I affix my signature in presence of two witnesses.

ORVILL W. BROWN.
